US0D1075814S

(12) United States Design Patent (10) Patent No.: US D1,075,814 S
(45) Date of Patent:  May 20, 2025

(54) DISPLAY PANEL OR PORTION THEREOF WITH GRAPHICAL USER INTERFACE

(71) Applicant: NCSOFT Corporation, Seoul (KR)

(72) Inventors: Sung Mi Park, Gyeonggi-do (KR); Yea Ji Ki, Gyeonggi-do (KR); Jong Hae Won, Gyeonggi-do (KR); Dan Bi Bae, Gyeonggi-do (KR); Young Ah Kim, Gyeonggi-do (KR); Hyo Joo Kim, Gyeonggi-do (KR); Ji Hee Moon, Gyeonggi-do (KR); Sung Woo Park, Gyeonggi-do (KR); Joo Won Lee, Gyeonggi-do (KR); Bo Min Kim, Gyeonggi-do (KR); Bo Yun Kang, Gyeonggi-do (KR); Kyeong Dae Kim, Gyeonggi-do (KR); Tae Eun Kim, Gyeonggi-do (KR)

(73) Assignee: NCSOFT Corporation, Seoul (KR)

() Term: 15 Years

(21) Appl. No.: 29/922,269

(22) Filed: Dec. 21, 2023

(51) LOC (15) Cl. 14-04

(52) U.S. Cl.

USPC D14/489

(58) Field of Classification Search

USPC D14/485-495

CLAIM

The ornamental design for a display panel or portion thereof with graphical user interface, as shown and described.

DESCRIPTION

The FIGURE is a front view of a display panel or portion thereof with graphical user interface, showing our design. The broken lines depict the portion of the display panel and form no part of the claimed design.

1 Claim, 1 Drawing Sheet
